FIG. 4.

Inventor
Mose Cobacker

By Ong & Bair Attys.

UNITED STATES PATENT OFFICE.

MOSE COBACKER, OF DES MOINES, IOWA.

AUTOMATICALLY-ADJUSTABLE CUFF-LINK.

1,358,291.

Specification of Letters Patent.

Patented Nov. 9, 1920.

Application filed July 12, 1919. Serial No. 310,483.

To all whom it may concern:

Be it known that I, MOSE COBACKER, a citizen of the United States, and a resident of Des Moines, in the county of Polk and 5 State of Iowa, have invented a certain new and useful Automatically-Adjustable Cuff-Link, of which the following is a specification.

The object of my invention is to provide 10 a cuff link, which is of simple and durable construction, in which means are provided for connecting the end members with each other for permitting adjustment, so that the link may have different lengths, while 15 normally retaining its shortest length.

More particularly it is my object to provide 20 a cuff link, having end members, and having simple means for yieldably connecting the end members together in such a way, which will leave no parts which will catch on the clothing or person.

With these and other objects in view my invention consists in the construction, arrangement and combination of the various 25 parts of the device, whereby the objects contemplated are attained, as hereinafter more fully set forth, pointed out in my claim, and illustrated in the accompanying drawings, in which:

30 Figure 1 shows a top or plan view of a cuff link embodying my invention.

Fig. 2 shows a horizontal, sectional view taken on the line 2—2 of Fig. 1.

Fig. 3 shows a vertical, transverse, sectional view taken on the line 3—3 of Fig. 1.

Fig. 4 shows a perspective view of one of the loops in incomplete form; and

Fig. 5 shows a perspective view of the other loop.

40 It is well-known that with the ordinary cuff links now used, the links hold the cuff ends so close together that the cuff cannot be drawn over the hand without releasing one end of the link from the cuff, nor can 45 the cuff be drawn up on the arm without releasing one end of the link.

It is my purpose to provide a link automatically adjustable in length, but normally held at its shortest length. For this purpose 50 I have provided a cuff link comprising the ordinary end members indicated by the reference characters 10 and 11, which may be artistically made in any suitable way.

55 Connected with the under or inner surface of each end member 11 preferably

rigidly is a ring 12. These rings in the assembled cuff link are arranged substantially at right-angles with relation to each other, as illustrated in Figs. 1 and 2. For 60 connecting the respective end members 10 and 11 for permitting automatic adjustment I have provided the following means.

An elongated loop 13 is made preferably of a flat strip of resilient metal. At one 65 end of the loop the end portion is provided with opposite notches 14 to receive the ring 12, as illustrated in Figs. 1 and 2.

At the other end of the loop 13 are opposite tongues 15. A second elongated loop 70 is provided having the opposite inwardly opening channel-shaped side members 16. The side members are connected at one end by the end members 17, provided with opposite notches 18 to receive the ring 12 of 75 the end member 11, in the manner illustrated in Figs. 1 and 2.

The second loop is made of resilient material and has at one end a flat end member 19 which is inserted through the loop 13 and 80 fits snugly between the sides thereof. One end of the member 19 is preferably connected integrally with one of the side members 16, and after having been inserted between the sides of the loop 13 is soldered to the 85 other side member 16.

The end member 19 is narrower than the side members 16, so that when the device is assembled in completed form, the side members 16 overlap the edges of the sides of the 90 loop 13, for forming a casing for a coil spring 20.

It will be understood that the coil spring 20 is placed between the loops before the end 95 is closed.

The tongues 15 slide in the channels 16 and said tongues with the end member 19 prevent any rotation of the loops with relation to each other.

The tension of the spring 20 is such as to 100 normally hold the loops in their contracted positions for holding the completed cuff link at its shortest length.

It will be obvious, however, that when the opposite sides of the cuff are pulled apart, 105 the link members 10 and 11 may be spread for contracting the spring 20 and extending the total length of the cuff link. The link will thus automatically stretch for permitting the cuff to be slid over the hand or up 110 on the arm, and will automatically contract when the cuff is at the wrist.

The advantages of such a structure are obvious from the foregoing description.

With a cuff link of the kind shown herein, the cuff will be held with its edges close together when on the wrist but may easily and automatically be opened when slid over the hand or upon the arm.

I desire to cover by my claim the use of any suitable material for the purpose, and 10 any modifications of structure or mechanical equivalents which may be reasonably included within the scope of such claim.

I claim as my invention—

A cuff link comprising end members, 15 means for connecting said end members comprising an elongated loop made of a flat strip of stiff material, having opposite

notches at one end, a ring on one end member received in said notches, said loop having opposite tongues at its other end, a second loop comprising inwardly opening channel-shaped side members, an end member connecting said channel-shaped members at one end, formed with opposite notches, a ring extended through said notches and connected with the other end member, a flat end member connecting the other end of said second loop, one end of said first loop being extended through said second loop with said tongues received in said channels, and a 20 25 spring received between said loops.

Des Moines, Iowa, July 9, 1919.

MOSE COBACKER.
